UNITED STATES PATENT OFFICE.

EDWARD ELLIOTT, OF CALUMET, MICHIGAN, ASSIGNOR OF ONE-HALF TO RICHARD D. JONES,
OF CALUMET, MICHIGAN.

DUSTLESS ASH-SIFTER.

No. 872,560.

Specification of Letters Patent.

Patented Dec. 3, 1907.

Application filed April 17, 1907. Serial No. 368,734.

To all whom it may concern:

Be it known that I, EDWARD ELLIOTT, a citizen of the United States, residing at Calumet, in the county of Houghton and State 5 of Michigan, have invented certain new and useful Improvements in Dustless Ash-Sifters, of which the following is a specification, reference being had to the accompanying drawings.

- 10 My invention relates to improvements in ash sifters; and an object of my invention is to provide an ash sifter which will prove simple in construction, cheap in manufacture and efficient in operation.
- 15 A second object of my invention is to provide an ash sifter which by its construction will prevent the escape of dust and which, therefore, will be cleanly in operation.

In the drawings illustrating the principle 20 of my invention and the best mode now known to me of applying that principle, Figure 1 is a perspective view of my new ash sifter; Fig. 2 is a central transverse vertical section; Fig. 3 is a central longitudinal section 25 of the rotary sieve; Fig. 4 is a plan view with the door and the sieve removed; and Fig. 5 is a detail of the sieve construction.

The corners of the wooden casing or box *a* are reinforced with metal corner pieces *b*; 30 and to the top of the box *a* is hinged the cover *c* covered with sheet metal *d*. The upper edge of each side of the box *a* is provided with a tongue *e* adapted to engage in a groove *f* in the opposed edge of the cover *c*. When 35 the cover is closed down upon the box, this tongue-and-groove construction prevents the escape of dust between the cover and the box. The front of the latter is provided with a door *g* hinged thereto; and around the 40 opening closed by this door are projections *h* which the edges of the door in its closed position overlaps so as to prevent the escape of dust from the lower compartment *i*. In this lower compartment is placed a suitable 45 receptacle *j* for the ashes which fall thereinto through the metal chute *k* the top of which

lines the upper part of the interior walls of the box and makes it practically fireproof. The box *a* is provided with suitable bearings *m*. 50

Each head *n* of the drum or rotary sieve *o* is lined with metal *p* as a protection against hot cinders. The sieve is two-part, the part *q* being hinged to the part *r* and being locked in place by the pins *s* each of which passes 55 through a staple *t* and over a hasp *u* in engagement with the latter. Extending axially through the drum is a sleeve *v* through which passes the shaft *w* held in place by the locking nuts *x*. Upon one end of the shaft 60 *w* is suitable secured the crank or handle *y*. The ends *v'* of the sleeve *v* are reduced and squared; and upon each squared end is mounted a bar *z* secured to the head of the drum. (Figs. 3 and 5). 65

The cover is held in place by the engagement of the hook *2* in the eye *3*; and the door is held closed by means of the button *4*.

The sieve can be dumped by removing it 70 from the box (Fig. 1) and unlocking the part *q* from the part *r*; or by rotating the drum after the parts *q* and *r* have been released from each other, when the cinders will fall through the chute into the pail below. Two 75 pails are preferably furnished with each sifter, one for ashes and one for cinders.

I claim:

An ash sifter consisting of a casing; a shaft journaled in said casing; a sleeve mounted upon said shaft, the ends of said 80 sleeve being squared; straps mounted upon said squared ends; and a sieve secured to said straps and mounted upon said shaft.

In testimony whereof I hereunto set my hand this 4th day of April, A. D., 1907, in 85 the presence of two witnesses.

EDWARD ^{his} X ELLIOTT.
mark
